US0D1084668S

(12) United States Design Patent (10) Patent No.: US D1,084,668 S
(45) Date of Patent: * Jul. 22, 2025

(54) COMB

(71) Applicant: Yujie Dai, Zhongxiang (CN)

(72) Inventor: Yujie Dai, Zhongxiang (CN)

() Term: 15 Years

(21) Appl. No.: 29/984,171

(22) Filed: Jan. 14, 2025

(30) Foreign Application Priority Data

Nov. 11, 2024 (CN) 202430712674.9

(51) LOC (15) Cl. 04-02

(52) U.S. Cl.

USPC D4/100; D24/214

(58) Field of Classification Search

USPC D4/100, 102, 114, 116, 117, 118, 119,
